UNITED STATES PATENT OFFICE

JULIAN W. MORTON, OF LINVILLE, NORTH CAROLINA

GOLF CLUB

Application filed March 20, 1931. Serial No. 524,103.

The invention relates to improvements in golf clubs having blades of the lofted type and more especially to niblicks or similar clubs employed for extricating golf balls 5 from sand traps, soft soil, lies in "rough", in water, or other situations requiring a high trajectory shot of comparatively short range.

The invention is illustrated in the accompanying drawings, in which:—

10 Fig. 1 is a fragmentary elevation of a golf club involving the invention, the blade of the club being shown in transverse section.

15 Fig. 2 is a similar view illustrating the action of the club in playing the ball from a partly submerged lie.

Fig. 3 is a face view of the club head.

Fig. 4 is a rear view of the same.

Referring to the drawings, 1 indicates the shaft of the club, 2 the shank or hosel in which the end of the shaft is fitted, the hosel being formed as an integral part of the blade 3, the hosel and blade constituting the head of the club. As indicated, the blade is "lofted" or inclined at an angle to the longitudinal axis of the shaft, so that, when the shaft is held in a substantially perpendicular plane in addressing the ball, the front face of the blade is inclined rearwardly and upwardly, so that, when the ball is impacted by the center of the face of the blade, it will be forced upwardly in a so-called pitch shot involving a relatively steep trajectory or arc of flight. Clubs of this character, of which the niblick is a typical example, are employed for pitching the ball out of sand traps, boggy lies, water hazards and lies in the rough. In playing a shot under the various conditions mentioned, it is difficult to prevent the front edge of the blade from penetrating too deeply into the sand, soft soil or water and, when such an undue penetration occurs, the stroke is faulty and fails, in most instances, to extricate the ball from the difficult position in which it lies, the usual result being to jump the ball a relatively short distance, so that an additional stroke or strokes with the club are necessary to effect the extrication of the ball.

50 The object of the present invention is to provide the blade of a golf club of the type in-

dicated with a wing or projection on the back or rear face of the blade of such a character as to prevent the blade cutting too deeply into the surface on which the ball lies, but which will have the effect of deflecting the blade 55 of the club upwardly, upon impact with the ball, thereby forcing or pitching the ball upwardly in a relatively steep trajectory or line of flight toward the objective. In its preferred form, the wing or projection on the 60 back or rear face of the blade takes the form of an integral rib 4 extending longitudinally of the back of the blade and joining the latter between the longitudinal axis and the rear edge thereof, the front face of the wing curv- 65 ing downwardly and forwardly to form a pocket. As shown, the front face 6 of the wing is concaved or arcuate and terminates in a hook-like lower portion 5, which, when the club is held perpendicularly with the 70 front edge or toe of the blade engaging the ground, lies a short distance above the ground and is substantially parallel therewith. The rear surface of the wing may be finished in any desired way, but is preferably rounded 75 or concaved longitudinally of the blade to merge into the surface of the back thereof, as indicated at 7. Preferably, the end sections of the wing are curved downwardly to merge into the back of the blade. 80

By reference to Fig. 1, it will be seen that, when the club is swung to engage the front edge of the blade 3 immediately between the ball and the surface on which it lies, the sand or turf, which is excised by the edge of the 85 blade, piles up or collects in the pocket formed by the forwardly curved wing 4 and forms a cushion or deflecting surface, which tends to deflect the club upwardly and prevents the forward edge of the blade digging deeper into 90 the surface, with the result that the ball is engaged by the lofted face of the club and pitched out of the sand or other difficult lie toward the objective. Playing a ball from a partly submerged lie is one of the most difficult strokes in golf, but, with a club of the character described, such a stroke may be made with ease and facility, as the pocket formed by the forwardly curved wing produces an air cushion, which prevents the blade 95 100

cutting too deeply into the water, but, on the other hand, tends to lift the blade as the latter impinges the partly submerged ball, thereby forcing the ball upward and away in the 5 desired steep arcuate flight toward the objective.

While the club is of special utility in playing the ball from sand traps, loose soil and water lies, it is also useful in playing the ball 10 from the rough or high grass where the usual tendency is to drive the forward edge of the blade too deeply into the surface on which the ball lies, as, in such case, the lower lip of the wing engages the surface and tends to force 15 the blade upward during the continued stroke.

While the improvement has been described with particular reference to golf clubs of the niblick type, it will be understood that it is adaptable to other clubs having lofted or 20 inclined impact faces designed to effect a so-called pitch shot involving the driving of the ball in the desired direction with a relatively high trajectory or arc of flight.

What I claim is:

- 25 1. A golf club, comprising a blade of the lofted type having a longitudinal wing on its rear face adjacent the rear edge of the blade and projecting forwardly toward the front edge of the blade.
- 30 2. A golf club, comprising a blade having a longitudinal wing projecting from its rear face and curved toward the forward edge of said blade to form an open pocket facing toward said front edge.
- 35 3. A golf club, comprising a blade having a longitudinal wing projecting from its rear face between the rear edge and the longitudinal axis of said blade, said wing being curved toward the front edge of the blade to 40 form a forwardly facing pocket.
- 45 4. A golf club, comprising a blade having a longitudinal wing projecting from its rear face, the front face of said wing being concaved to form a forwardly facing pocket.
- 50 5. A golf club, comprising a blade having a forwardly directed longitudinal wing projecting from its rear face between the rear edge and the longitudinal axis of said blade, the wing being of a height to just clear the 55 ground when the front edge of the blade rests on the ground in the normal position of the club in addressing a golf ball.
- 60 6. A golf club, comprising a blade having a forwardly facing hook-shaped wing projecting from its back between the rear edge and the longitudinal axis of said blade.

In testimony whereof I affix my signature.
JULIAN W. MORTON.
